United States Patent Office.

W. H. CARPENTER, OF NEW YORK, N. Y.

Letters Patent No. 80,910, dated August 11, 1868.

IMPROVEMENT IN FORM-BLOCKS FOR BASKETS.

The Schedule referred to in these Letters Patent and making part of the same.

TO ALL WHOM IT MAY CONCERN:

Be it known that I, W. H. CARPENTER, of the city, county, and State of New York, have invented a new and useful Improvement in Form-Blocks for Shaping and Finishing Baskets; and I do hereby declare that the following is a full, clear, and exact description of the same, reference being had to the accompanying drawings, forming a part of this specification, in which—

Figure 1 represents a vertical section of a form-block constructed according to my improvement, and

Figure 2 represents a plan of the same as seen from above.

Similar letters of reference indicate corresponding parts in both figures.

This invention is more especially designed to facilitate the removal of finished baskets from the block or former upon which they are placed in the operation of manufacture, and to this end it consists in a novel construction of a form-block, composed of movable parts or sections, so combined with a supporting-ring and an operating-wedge, or their equivalents, as to provide an efficient means of securing the desired result.

In order that others may be better enabled to understand the construction and operation of this improvement, I will proceed to describe it with reference to the drawings.

A represents a stand, of any suitable construction, in the centre of which is placed a vertical shaft, B, the upper end of which is made tapering, so as to constitute a conical wedge, the lower end of which is connected with a treadle, C, by means of which the said shaft B may be forced upward.

D is a ring, sustained at a suitable distance above the stand A by rods, b, and the centre of which is directly over the centre of the conical wedge B.

E are movable parts or sections, three or more parts of which when united compose the form-block. Each of these movable-sections E is provided with a groove, e, cut in the under side of the top or horizontal portion, near the inner surface of its perpendicular walls, and designed to receive that portion of the ring D upon which the said section is sustained when the apparatus is in use. Each section E is also provided with an inwardly-extending base-piece, d, into which is cut a slot or opening, g, which passes over one of the upright rods b, thereby retaining the said section in place upon the stand.

h is a groove, cut in the outer surface of the sections, near their lower extremities, for reception of the basket-hoop.

In using this invention, the basket-hoop is first placed in the groove h, and the basket is then placed upon and around the sections E, the combined external form of which corresponds to that which it is intended to give the basket. The basket is then secured to the hoop in the usual manner, after which the shaft or conical wedge B is forced upward by means of the treadle C, and the tapering end of said shaft B forcing apart the lower portions of the sections E, causes them to expand against the internal surface of the basket with such pressure that the continued upward movement of the shaft will lift the sections E, with the basket thereon, away from the ring D, so that the shaped and finished basket may be readily removed from the apparatus.

What I claim as my invention, and desire to secure by Letters Patent, is—

The combination of the expanding or movable sections E, the supporting-ring D, and the conical wedge B, substantially as and for the purpose herein specified.

W. H. CARPENTER.
